CLAIM

We claim the ornamental design for linkage assembly for use with push button latch and lock operating assemblies, as shown and described.

DESCRIPTION

FIG. 1 is a perspective view showing principally top, front and right features of a first embodiment of linkage assembly for use with push button latch and lock operating assemblies, embodying our new design, with the arms thereof pivoted to an extended position:

FIG. 2 is a top plan view thereof;

FIG. 2 is a top plan view thereof;
FIG. 3 is a front view thereof;

FIG. 3 is a front view thereof;
FIG. 4 is a bottom view thereof;

FIG. 4 is a bottom view thereof;

FIG. 5 is a rear view thereof,
FIG. 6 is a perspective view showing principally top, front and right features of a second embodiment of linkage assembly for use with push button latch and lock operating assemblies, embodying our new design, with the arms thereof pivoted to an extended position:

FIG. 7 is a top plan view thereof;

FIG. 7 is a top plan view thereof;
FIG. 8 is a front view thereof;

FIG. 8 is a front view thereof; and

FIG. 9 is a bottom view thereof.
